LAST FOR USE IN MAKING PLASTIC FOOTWEAR
George H. Bingham, Jr., Westminster, Md., assignor to
Cambridge Rubber Company, Taneytown, Md., a cor-
poration of Maryland

Filed Feb. 5, 1958, Ser. No. 713,433
7 Claims. (Cl. 18—41)

This invention pertains to the manufacture of water-
proof footwear, for instance boots, bootees, gaiters, etc.,
in particular to footwear of the kind in which a synthetic
plastic is employed as a waterproofing medium instead
of natural rubber, and relates more especially to a novel
last for use in making such footwear.

In the co-pending application of George H. Bingham,
Jr., Serial No. 707,505, filed January 7, 1958, now Patent
No. 2,957,188, there is disclosed a method of making a
boot whose upper, at least, consists of synthetic resin,
and which has an opening extending downwardly from its
top with a conventional slide fastener for closing the
opening, said application suggesting a novel method of
uniting the tapes of such a fastener to the inner surface
of the upper and likewise the bonding of a simple rein-
force tape to the upper. While the method disclosed in
said application is much superior to any method which
is known to be in commercial use, some difficulties have
been experienced in the practice of said method: first, be-
cause the plastics employed in making such footwear have
no adhesive qualities in the unfused state; and second,
because the surface of the boot to which the fastener tapes
are to be secured (in particular when the fastener is to
be located at the front of the boot) is of non-uniform
width and is curved both transversely and up and down
to varying degrees of curvature, and since the fastener
tape is not stretchable, it is very difficult to conform this
tape to the inner surface of the boot top so as to insure
a strong adhesion between the parts. When herein refer-
ence is made to a "tape," the term "tape" is to be
understood (unless otherwise defined) as inclusive of a
single length of tape or of the two parallel tapes com-
prised in a slide fastener.

A principal object of the invention is to provide a novel
last, which is useful in the practice of the above process
whereby it is made possible firmly to attach a tape or tapes
(for example the tapes of a slide fastener) to the interior
of a plastic boot upper by adhesive means and without
recourse to the customary heat-sealing process. A further
object is to provide means whereby a shoe upper may be
so shaped, without detriment to its salable char-
acteristics, as to facilitate the adhesive bonding of a tape
or tapes to the interior of the boot upper. A further
object is to provide a novel last which may, if desired,
be employed directly in making plastic boots by the
dipping method, or which may be employed as a model in
the making of a hollow mold for use in molding a plastic
boot by the slush method, or a modification of the slush
method, thereby to impart to the mold a shape such
as to make possible the making of a boot upper having a
specially shaped area or areas to which a woven textile
tape may readily be conformed as a step in uniting it
adhesively to the inner surface of the upper. Other and
further objects and advantages of the invention will be
pointed out in the following more detailed description
and by reference to the accompanying drawings wherein:

FIG. 1 is a side elevation of a last useful in the prac-
tice of the present invention;

FIG. 2 is a front elevation of a last embodying the
invention;

FIG. 3 is a rear elevation of the last of FIG. 2;

FIG. 4 is a transverse section in any horizontal plane
through that part of the last corresponding to the loca-

2

tion of the tape, for example on the line 4—4 of FIG. 1;
FIG. 5 is a transverse section on the line 5—5 of
FIG. 3;

FIG. 6 is a side elevation of a last illustrating another
embodiment of the invention;

FIG. 7 is a vertical section on the line 7—7 of FIG. 6;

FIG. 8 is a section in any horizontal plane through
that part of the last corresponding to the location of the
tape, for example on the line 8—8 of FIG. 7;

FIG. 9 is a transverse section similar to FIG. 8, but
illustrating a modification; and,

FIG. 10 is a section similar to FIG. 5, illustrating a
modification.

Referring to the drawings, the numeral 10 designates
a boot last embodying the present invention. This last
comprises the foot portion 11 and the leg portion 12.
This last is of generally conventional construction and,
as indicated in FIG. 4, of more or less elliptical shape
in transverse section, but, in accordance with the present
invention, having areas 13 and 14 at its front and rear,
respectively, which are of uniform transverse width from
end-to-end and which, in the illustrated embodiment, are
rectilinear in transverse section, although being curved
heightwise of the last. While areas which are trans-
versely flat are preferred, it is contemplated that areas
of uniform width heightwise of the last, but which are
slightly curved to the same radius at all transverse sections
may be employed. Flat areas of uniform width may be
formed by taking the ordinary last and grinding away
some of the material, as indicated in dotted lines in FIG.
4, so as eventually to provide the surfaces 13 and 14.
These surfaces, at any horizontal plane of the leg portion
of the last section, are rectilinear so that the surface
13 or 14, as a whole, may be described in geometrical
terms as "cylindrically curved," that is to say, the surface
is such as is generated by the motion of a horizontal
straight line in moving downwardly through space while
always parallel to itself and while following a directrix
line which may, as respects FIGS. 1, 2 or 3, be considered
to be the center line of the usual last at its forward or
rear part, respectively. Within said definition, the direc-
trix line may be any curvature or even straight. When
hereinafter this surface is referred to as of "cylindrical"
curvature, this term is to be interpreted in accordance with
the above definition.

While it is possible to form these surfaces 13 and 14
by grinding away some of the material of the last, a
preferred mode of procedure is to set into the substance
of the last, at the desired location, a ribbon-like strip
13^a or 14^a, respectively, of steel or other hard material
which has previously been shaped to the desired height-
wise curvature. These strips are so set into the sub-
stances of the last proper that their exposed surfaces
merge smoothly with the adjacent portions of the surfaces
of the last proper. Such strips may be made in accord-
ance with a preshaped template having the desired curva-
ture. Such strips, embedded in the material of the last,
insure uniformly in the making of successive lasts. It is
contemplated that these strips may be set into the mold
in which the last is formed so that the strips are em-
bedded in the material of the last during the molding
operation.

In FIGS. 1 to 5, the last is shown as having such a
cylindrically curved surface, both front and rear, but
it is to be understood that the last may be provided with
such a surface either at front or rear rather than having
two such surfaces. The surface at the front of the last
is designed to facilitate the application of a slide fastener
at the front of the boot which is to be made on the last,
while that at the rear is particularly intended for use in
applying a reinforce tape to the back of the boot.

In FIGS. 6 to 8, the last 16 is shown as having a surface such as above described at its side rather than at the front or rear. Slide fasteners are often installed at the side of a boot. This surface is indicated at 19 and, as shown in FIG. 8, may be the exposed surface of a preformed strip embedded in the substance of the last, it being noted that in any case in which such an embedded strip is employed, the exposed outer face of this strip will merge smoothly with the adjacent portions of the peripheral surface of the last proper. The strip, as shown in FIGS. 6 and 7, is anchored to the last proper by inserted pins or screws although it may be spot welded to the last proper or may be embedded in the material of the last proper and permanently united to the latter during the molding of the last.

In FIG. 9, the last 20 is shown as having the surface 21 at its side, such surface being a portion of the last itself, the latter having been ground away as indicated by the dotted line in forming this flat surface.

In the practice of the method set forth in the aforesaid co-pending application for Letters Patent, use is made of an appliance which clamps the tape or tapes to the boot upper to insure firm contact of the parts while they are being bonded together. No particular difficulty is experienced in preparing a suitable clamping appliance for use in bonding a tape to the side or back of a boot upper for, at these parts of the upper, the curvature of the upper, both heightwise and transversely of the upper, is slight and does not vary greatly among boots of different sizes and styles so that the same clamping appliance is useful in making a substantial variety of boots. However, at the forepart of the boot upper where slide fasteners are customarily installed, the curvature is substantial and of varying radius, both heightwise and transversely of the boot upper, and varies with different styles and sizes of boot so that it would seemingly be necessary to provide clamping devices in a great number of shapes in order to make the above process of general application. In the effort to overcome the difficulty just referred to, extended experiment was made to determine the possibility of providing an embedded strip, such as the strip 13^a above referred to, which would be applicable to lasts of different styles and sizes and thus make a given clamping appliance of a greater range usefulness. With this in view, a number of lasts were selected (those selected being lasts intended for use in making gaiter-type boots since these are the most accurately designed of those employed in the making of rubber footwear so far as fit is concerned). One of the lasts so selected was of a shape designed for making a gaiter with a flat heel, that is to say, one having a heel up to 1 inch in height; a second, for making a shoe having a Cuban heel, that is to say, one having a heel of from 1½ inches to 2 inches in height; and a third, for use in making shoes having a high heel, that is to say, for heels of from 2½ inches to 3½ inches or higher. Having selected these lasts, a center line was scratched on the front of each last indicating the position at which the center of width of a slide fastener should be located on a shoe made on such a last. A profile was then made of the curve formed by this line. Such profile would have the shape of the forward edge of a vertical front-to-rear section of the last in the plane of its central line. These several profiles were superposed and from these a composite curve was drawn which was essentially the average shape of the three profiles. A template was then made having the shape of this composite curve. When this template was fitted to lasts of various types and sizes, it was found that it would fit very closely to the fronts of lasts of many styles and including those designed for women's children's men's, boys' and youths' wear, and designed for making shoes having heels of various heights. Having ascertained this fact, this template was then employed in making steel strips such as those above referred to for insertion in the front portion

of a last; and, upon making lasts having such steel strips embedded therein, it was found that it was possible by the use of the lasts thus prepared to carry out the process of the aforesaid co-pending application by the use of 5 clamping appliances of a very limited number of sizes, thus making the method wholly practicable from the commercial standpoint. It will be understood that the inserted strips of the last, shown in FIGS. 2, 3 and 5, are desirably made according to the above method of procedure; and, 10 likewise, that when the cylindrically curved surfaces of the last are made by grinding, as suggested in FIGS. 1 and 4, the heightwise curvature of the finished surface will likewise be made according to a template prepared as above suggested.

15 As already suggested, while a surface which, at any transverse section, is rectilinear, is preferred, some of the advantages of the invention may be obtained, especially at the front or back of the last, if the surface of the uniformly wide area be slightly bowed or curved in transverse 20 section, to the same radius at all such sections. Such an arrangement is illustrated in FIG. 10, wherein the last 22 is shown as having, at its front and rear, inset strips 22 and 23, which like the strips 13^a and 14^a extend heightwise of the last at locations corresponding to those 25 at which tapes are to be placed in the shoe upper, and which are of uniform width from end-to-end, but which are slightly bowed, to the same radius, at all transverse sections, the longitudinal curvature to the strips corresponding to those of strips 13^a and 14^a.

30 However, it should be noted that, while the above procedure is desirable and preferred, the cylindrically curved surfaces may be formed in accordance with other procedures within the scope of the appended claims.

I claim:

35 1. A last for use in the manufacture of an article of footwear such as a boot whose upper, at least, is of a synthetic plastic and which includes a length of textile tape adhesively bonded at the inner surface of the upper, the peripheral surface of the leg portion of the last comprising 40 a cylindrically curved area which, at any transverse section of the last, is rectilinear, said area being of substantially the uniform width of said tape heightwise of the last and of a curvilinear length approximating the length of the tape which is to be adhered to the boot upper, the edges of said area merging smoothly with the adjacent peripheral surface of the last proper at all points heightwise of the last.

2. A last, according to claim 1, wherein said cylindrically curved area is of a transverse width approximately 50 equal to the total width of a conventional slide fastener.

3. A last, according to claim 1, wherein said cylindrically curved area is located at the front of the leg portion of the last.

4. A last, according to claim 1, wherein said cylindrically curved area is located at the side of the leg portion of the last.

5. A last, according to claim 1, wherein said cylindrically curved area is located at the rear of the leg portion of the last.

60 6. A last for use in the manufacture of an article of footwear such as a boot whose upper, at least, is of a synthetic plastic and which includes a length of textile tape adhesively bonded at the inner surface of the upper, the leg portion of said last being of approximately elliptical 65 transverse section but varying in transverse area from point-to-point heightwise and having a ribbonlike strip of hard material embedded in the substance of the last at the location at which the tape is applied to the boot upper, said strip approximating in width and length the tape which is to be used in the boot to be lasted upon said 70 last, said strip being curved heightwise of the last to conform to the curvature of the latter and being rectilinear at the surface at any transverse section therethrough, the edges of the exposed surface of said strip merging smoothly with the adjacent peripheral surface of the last proper

at all points heightwise of the last, said last having means securing the strip to the last proper.

7. A last, according to claim 6, wherein said strip is located at the front of the leg portion of the last, and wherein the surface of the strip is of a transverse width approximately equal to the total width of a conventional slide fastener.
